(57) **CLAIM**

The ornamental design for an excavator bucket, as shown and described.

DESCRIPTION

The present application is also related to U.S. Design application Ser. No. 29/719,364, U.S. Design application Ser. No. 29/719,367, and U.S. Design application Ser. No. 29/719,368, all of which are concurrently filed herewith, and the disclosures all of which are incorporated herein by reference.

FIG. 1 is a front perspective view of an excavator bucket according to our design;

FIG. 2 is a rear perspective view thereof;

FIG. 3 is a front view thereof;

FIG. 4 is a top plan view thereof;

FIG. 5 is a rear view thereof; and,

FIG. 6 is a right side view thereof, the left side view being a mirror image thereof.

The broken lines shown in the drawings are for the purpose of illustrating environmental structure that forms no part of the claimed design.

1 Claim, 6 Drawing Sheets
